RECEPTACLE COVER PLATE

Shinjiro Mori, Tokyo, Japan, assignor to Mori Denki
Manufacturing Co., Ltd., Osaka, Japan

Filed Feb. 12, 1974, Ser. No. 441,825

Claims priority, application Japan Aug. 19, 1973

Term of patent 14 years

Int. Cl. D8—09

U.S. Cl. D8—184

FIG. 1

FIG. 2

FIG. 3

FIG. 6

FIG.4 FIG.5 FIG.7

FIG.8

FIG. 1 is a front elevational view of the receptacle cover plate showing the new design;

FIG. 2 is a rear elevational view thereof;

FIG. 3 is a top plan view thereof;

FIG. 4 is a side elevation thereof viewed from the right side of FIG. 1;

FIG. 5 is a side elevation thereof viewed from the left side of FIG. 1;

FIG. 6 is a sectional view thereof taken along the lines 6—6 of FIG. 1;

FIG. 7 is a sectional view thereof taken along the lines 7—7 of FIG. 1; and

FIG. 8 is a perspective view thereof.

I claim:

The ornamental design for a receptacle cover plate, as shown and described.
